MARKING TAG STRIP

Frederic L. Rieger, Dayton, Ohio, assignor to The Monarch Marking System Company, Dayton, Ohio, a corporation of Ohio

Application June 13, 1949, Serial No. 98,715

3 Claims. (Cl. 281—5)

This invention relates to tag strips utilized in automatic marking machines. More specifically, the invention is directed to a new family of tag strips having certain advantages and features not present in tag strips provided heretofore.

The present strips are particularly adapted to use in marking machines of the type disclosed in United States Letters Patents Numbers 2,328,934 and 2,372,460 modified by a new cut-off knife which is disclosed in my co-pending application for a "Tag Marking Machine Cut-off Knife," Serial Number 98,269, filed June 10, 1949, now Patent No. 2,586,383.

In these machines the tag strip is advanced intermittently across a table to a station where the tags are printed and then severed from the strip. The advancing motion is imparted to the strip by feed fingers which engage in notches in the strip. The machines are cyclic in nature with all of the parts functioning in set sequence. In each cycle there is an advance, a printing and a cut-off. Heretofore, these machines could operate only on single width tags because of the cyclic cut-off. A double tag having two panels could be printed properly, that is, each panel could be impressed but there was no way to arrange the cut-off operation to occur only between complete tags without making extensive and elaborate changes in the driving mechanism. The new tag strips provided here and the cut-off knife of my above mentioned co-pending application have solved this problem.

The tag strips of this invention are all designed on a basic pattern, the common denominator of the family, which is adapted to the operating functions of conventional marking machines modified by the cut-off knife referred to above. The family includes practically all of the desirable tag forms. Not only does it include single width tags of different sizes and double panel tags but it also includes multiple panel tags, tags with one or more tear-out panels, and grouped combinations of multiple and single panel tags. A strip of any one of these different tag forms may be fed through the marking machine without it being necessary to make adjustments or change the setting of any of the parts in changing from one form of strip to another. Thus, a marking machine's utility is greatly increased. Where in the past it was necessary to provide different machines for the different tags, with the present invention one machine can be used for marking all forms of tags.

In the preferred embodiment, each strip has a plurality of equally spaced feed finger notches cut through the material of the strip in a band extending longitudinally of the strip. In a strip of single panel tags these notches are between tags. In a strip of multiple panel tags, these notches are between panels as well as between complete tags. In the feeding operation, since the machines are designed to advance the strip a notch at a time, each panel is presented at the printing station where it is impressed with the marking data. Thus, every panel carries the same data and the tear-out panels of those strips having them, which are designed to be torn from the tags when the goods to which the tags are affixed are sold, provide complete records of the goods sold for inventory and the like purposes.

In strip form, the tags lie side by side, that is, they extend transversely of the strip. The tags are separated at the edges of the strip by pairs of aligned slots that are cut into the opposite margins of the strip. On the one edge of the strip each tag has a header portion de-

2

fined by these slots and in the multi-section tags the panels extend from this header across the strip. The panels of each tag are defined one from the other by a score along a line from the header to the edge of the strip opposite the header. This score is broken by the feed finger notch between the panels.

Each strip has two or more zones extending longitudinally of the strip across the panels in which the material of the strip is continuous for the entire length. The 5 continuity of the material in these zones provides strength to resist breakage of the strip. This is a rather important feature, because, during the step by step advance of the strip through the marking machine, the movement of the strip is intermittent, with the maximum stress being 10 put on the strip at the start of an advancing step. Inasmuch as the strip is usually fed into the machine from a spool, the inertia of the spool must also be overcome with each advance, thus adding to the drag on the strip. In the improved strip the feed finger notches are positioned between two of these continuous zones so that the stress of the feed fingers is carried by them.

The strips may be provided in different widths but in either the wide or the narrow strips, the longitudinal line of the feed finger notches is well within the bounds of the strip so that the tension forces on the strip during 15 the feeding operation are distributed to both, or in the instance of a wider strip, to three continuous bands of material. The feed finger notches, being relatively narrow, do not weaken the strip appreciably at the score lines, 20 and thus, there is little possibility of the strip breaking at these lines during the initial strip fabrication or during 25 subsequent use of the strip in a marking machine.

When the improved strip is operated on by the cut-off knife the material within the above mentioned longitudinal zones at the score lines between panels and between the individual tags is cut out. Thus, where these zones cross the score lines, that is, along the lines between panels, a substantial amount of material is removed and after a tag has been printed and dispensed from the 30 marking machine the tear-out panels may be torn from the body of the tag very easily. The cut-off knife is of the shear type, having a flat lower cutting edge rather than a sharpened edge. The cutting edge is broken into 35 shearing sections corresponding to the spacing and number of the longitudinal zones. The slots between tags, and the feed finger notches are as wide as the blade so that after a cut-off operation all of the connecting material between individual tags is removed, leaving smooth edges for the tags. Also after a cut-off operation the feed 40 finger notches on the score lines between sections are lengthened to a substantially long slot extending from the header to within a short distance of the lower marginal edge of the tag, leaving only a marginal connection at this edge between the panels. These severed tags 45 have an advantage over tags provided heretofore, in that the tear-out panels can be removed with a snap-like motion, breaking off cleanly, without the danger of either 50 the header or other panel of the tag being torn.

There is a further advantage, however, the long slot 55 is cut in the body of the tag without disturbing the connection of the material at the lower margin of the panels. Thus, when a tag is attached to goods, the continuous lower margin insures that the lower edge of the tear-out panel does not catch on obstructions and be inadvertently torn from the tag.

There is another feature in regard to the configuration 60 of the strip along the transverse score lines. Since the cut-off knife shears the strip only in those places defined by the above mentioned longitudinal zones, it follows that along these score lines the cut is broken. The 65 inventor provides small apertures or perforations to define the ends of the cuts of the knife where it pierces the scored lines. This results in rounded ends for the slots, adding considerably to the appearance of the tags after 70 they are dispensed from the marking machine. These 75 holes do not detract appreciably from the strength of the strip, inasmuch as they are small and are spaced.

Summarizing briefly, the new tag strip includes the following features: first, the zones in which the material of 80 the strip is continuous; second, the positioning of the equally spaced feed finger notches in the longitudinal band

between two zones; third, the disposition and form of the feed finger notches on the score lines between sections, plus their advantageous changed form after being severed from the strip; fourth, the use of feed finger notches and slots between the tags that are as wide as the cut-off knife blade so that smooth edges are provided between tags after the cut-off operation, and so that the notches between sections are in effect elongated by the cut-off operation; fifth, the transverse disposition of the sections or panels relative to the marginal header portion; and sixth, the small holes or perforations defining the ends of the cuts where the knife pierces the scored lines.

These features and others, which will be readily apparent from the description of the drawings, provide a tag strip having many advantages, the foremost being that strips made in accordance with the present disclosure may include grouped combination of different tags, individual multi-section tags, or any combination of tags that is desirable. Further, these different types of tags may be used in conventional marking machines without extensive adjustments or changes in the machine other than the mere substitution for the conventional knife of a knife of the type disclosed in the above mentioned copending application.

Examples of different types of tag strips which may be fabricated by using the principles of the present invention are disclosed in the following detailed description of the drawings in which:

Figure 1 shows a tag after being severed from the improved tag strip.

Figure 2 is a portion of a tag strip embodying the present invention.

Figure 3, which is enclosed in a bracket, shows a tag strip made in accordance with the present invention, a cut-off knife of the type which may be utilized in connection with the strip, and a tag severed from the strip. In this view the knife is turned at right angles to its normal cutting plane to illustrate diagrammatically the manner in which the knife acts upon the strip.

Figure 4 shows a multi-section tag of slightly different form.

Figure 5 illustrates a strip of tags of the type shown in Figure 4.

Figure 6 shows a modified form of the improved tag strip in which a group of tags is repeated throughout the length of the strip.

In general, each tag of the strips shown in the drawings includes a header portion 10, which may carry a company name, and the fastening means 11 for securing the tags to the articles to be marked. In this disclosure string-tags are shown but it will be obvious that other types of fastening means may be utilized with these strips, e. g., staples, pins, clips or the like.

Referring now to Figures 1 and 2, this particular tag strip includes three longitudinal zones 12, 13 and 14, in which the material of the strip is continuous throughout its length. In the strip, Figure 2, a plurality of equally spaced feed finger notches 15 is provided. These notches are spaced longitudinally of the strip in a band between the upper two longitudinal zones 12 and 13. Thus, in the feeding operation the pulling force of the feed fingers is distributed to the continuous zones of material.

In the marking machines to which the present tag strip is adaptable the feed fingers (not shown) are mounted in a carriage which reciprocates in timed sequence as part of the complete operating cycle, advancing the strip in steps from notch to notch. As each section of the strip comes under a printing head the head lowers and prints the strip with the characters carried in a type chase. Thus, every panel or section between two feed finger notches is impressed.

Where the respective longitudinal zones 12, 13 and 14 join individual tickets of the strip, the necks of material 16, 17 and 18 respectively are provided. These necks are defined, in order from the header margin to the lower margin, by upper marginal slot 19, feed finger notch 15, a notch or slot 21 and a lower marginal slot 22. It will be noted that these slots and notches are of the same width, this width being that of the cut-off knife, indicated generally at 23, in Figure 3, so that when the knife descends between individual tickets the three necks 16, 17 and 18 are completely removed leaving smooth side edges 24 and 25 for the severed tag as shown in Figure 1.

Referring now to the tag in Figure 1, two panels or sections are provided, one of these indicated by 26 is

integral with the header portion 10, the other, indicated by 27, is defined by the score line 28. Both panels depend from the header 10 and with respect to the strip extend transversely thereof. The panels 27 in the strip form are defined not only by the score lines 28, but also by the equally spaced feed finger notches 15. Also along the transverse portion of the score line 28, between sections, small round apertures or perforations 30 are provided. Each one of these apertures defines a terminal point for the cut made by the knife 23 when it descends between the panels. Thus, as shown in Figure 2, one of these perforations is at the inner corner of the panel 27, another at the lower side of the zone 13, and two others at both sides of the zone 14. When the knife operates on the strip between panels all of the material within the three zones is severed to the width of the feed finger notch 15. Therefore, with this particular type tag strip, when an individual tag is severed, the feed finger notch 15 is in effect lengthened to include the two perforations 30-30 at the respective outer edges of the zones 12 and 13 to provide the long slot 31. At this same time, the material within zone 14 is also severed to provide the shorter slot 32. These two slots 31 and 32, being aligned, weaken the joint between the two sections of the tag considerably and by placing one's thumb in the position shown diagrammatically at 33, the panel 27 may be removed with a snap-like motion severing the panel cleanly from the body of the tag.

Figure 3 illustrates diagrammatically the manner in which the tag strip is operated on by the cut-off knife 23; the tag strip being shown at the right, the severed tag shown at the left, and with the knife 23 between the two. In the drawing the knife is turned at 90 degrees to its normal operating position to show the configuration of the cutting edge. This particular tag strip has only two longitudinal zones 12 and 13 in which the material of the strip is continuous, and thus has only two necks 16 and 17 of material joining the individual tags in the strip. The dot-dash lines which are used to outline the two zones 12 and 13, it will be observed, outline two cutting edges 34 and 35 on the knife 23. Between these two edges 34 and 35 the knife edge carries a teat 36. This teat has an aligning function which is described in the above mentioned copending application. It will be noted that the two cutting edges 34 and 35 are angulated to provide a progressive shearing action when the blade descends on the strip and also that the teat 36 falls within the two zones 12 and 13 and enters a feed finger notch 15. This knife may be utilized in connection with any of the tag strips shown in the drawings. When it is being used with the strips shown in Figures 2, 5 and 6 a third cutting edge 37 cuts the material of the strip within the third zone 14. This third cutting edge is also set on an angle to provide the progressive shearing action. The edge of the blade between the two cutting edges 35 and 37 is notched out as at 38 to clear the strip between the two longitudinal zones 13 and 14. Thus, with the narrow strip shown in Figure 3, the lower margin 40 of the tags are not disturbed. On the wider strips, for instance the one shown in Figure 2, the notch 38 falls on the slot 21 between tags with the cutting edge 37 cutting out the neck 18 between adjoining tags. When descending on the scored line between panels, however, the cutting edge 37 takes out the material within zone 14, with the notch 38 falling on the scored line between the zones 13 and 14 leaving the small neck of material indicated at 41 between the two slots 31 and 32 (Figure 1). On these wider strips, the shank portion 42 of the knife, being recessed from the respective cutting edges, clears the lower margins of the tags to provide the continuous marginal edges 40.

The tag and strip shown in Figures 4 and 5 include a marginal tear-off panel 43 which is attached to the side of a double panel tag. In this strip each complete tag is defined by the necks of material 16, 17 and 18. Each tag also includes a neck 44 joining the upper end of the marginal tear-off strip 43 to the header portion 10. This particular tag includes the string fastener 11 but it is centered relative to the body portion of the double tag only. This strip, as does the others, includes the three longitudinal zones 12, 13 and 14 respectively, in which the material is continuous for the length of the strip. When the knife 23 descends on this strip between tags the three necks of material are cut out as with the other strips described above. However, when it descends on the transverse score line between the panels

43 and 27 the two slots 31 and 32 are cut but the connecting neck 44 remains. Also, with this strip it will be noted that the lower marginal edge 40 is undisturbed and is continuous for the width of the tag across all three panels.

In Figure 6 a modified form of the tag strip is shown. This particular modification illustrates the manner in which the invention can be utilized to provide tag strips comprising groups or sets of individual tags. One of these sets is indicated at 45 and is embraced by the bracket. This set includes two double panel tags and a single panel tag, the double panel tags being indicated by 46 and 47 respectively, with the single section tag indicated by 48. This set 45 of three tags is repeated throughout the length of the strip. Each of the double section tags of a set are similar to the tag shown in Figure 1 while the single panel tag 48 is plain.

As a slight modification of the strips disclosed here, in the initial fabrication the feed finger notches 15 between panels of the tags may be elongated so as to extend through zone 12 to the headers, taking in the aperture 30 at the inner corners of panels 27. Thus, zone 12 would be broken at the transverse score lines.

The tag strips shown are only representative of the different types of tag strips which may be formed by utilizing the principles of this invention. By applying these principles many other combinations of tag units may be incorporated in a single strip. It will be noted that the different examples in the drawings all include the spaced feed finger notches, the continuous zones, the small perforations on the scored lines, the elongated slot between panels after a tag has been operated on by the knife, and each tag, even after being operated on, has the continuous lower marginal edge 40. The principles disclosed herein may be applied to any number of combinations of tags making up a strip and these tags may be fed through a conventional tag marking machine having a knife similar to the one disclosed by the above mentioned copending application, with each complete tag being dispensed from the machine with the smooth cut edges and the section or panels, no matter how many in each tag, being undisturbed other than having the elongated slots cut in them to facilitate tear-off of the removable panels.

Having described my invention I claim:

1. A marking tag strip comprising a plurality of tags defined by pairs of marginal slots, the respective marginal slots of each pair being aligned transversely of the strip and extending toward one another from opposite sides thereof, each tag having a header portion at one side of the strip with panels extending from the header toward the opposite side of the strip, a plurality of identical and equally spaced feed finger notches cut through the strip, said notches being the same width as said marginal slots and aligned longitudinally of the strip, said notches disposed with a notch between each pair of adjacent tags in transverse alignment with said marginal slots and with a notch between adjacent panels in each of the tags, at least two zones extending longitudinally of the strip contiguous with and at the respective sides of the notches in which the material of the strip is continuous, the zone at the header side of the strip being closely adjacent said header, whereby upon operation on the strip of a cut-off knife designed to remove all of the strip material within said longitudinal zones successively between tags and between panels, the tags are separated and an elongated slot is provided between panels in each tag, said elongated slot extending from the header transversely of the tag.

extending from the header transversely of the tag toward the side thereof opposite the header.

2. A marking tag strip comprising a plurality of tags defined by pairs of marginal slots, the respective marginal slots of each pair being aligned transversely of the strip and extending toward one another from opposite sides thereof, each tag having a header portion at one side of the strip with a pair of panels extending from the header toward the opposite side of the strip, 10 said panels being of equal width with one of them being defined from the other by a score along a line extending transversely of the strip from the edge of the strip opposite the header to the header and one of them being defined from the header by a second score 15 along a line at right angles to the first score from the inner terminus of the first score to an edge of the tag, a plurality of identical feed finger notches cut through the strip within a band extending longitudinally of the strip, said notches disposed with a notch between each 20 pair of adjacent tags in transverse alignment with said marginal slots and with a notch between the panels of each tag, said notches being as wide as said marginal slots, and at least two zones extending longitudinally of the strip across the panels and contiguous with the 25 notches in which the material of the strip is continuous, the zone of the two said longitudinal zones which is nearer the header side of the strip being closely adjacent said second score.

3. A marking tag strip comprising a plurality of tags 30 defined by pairs of marginal slots, the respective marginal slots of each pair being aligned transversely of the strip and extending toward one another from opposite sides thereof, each tag having a header portion at one side of the strip with a pair of panels extending from the header toward the opposite side of the strip, said panels being of equal width with one of them being defined from the other by a score along a line extending transversely of the strip from the edge of the strip opposite the header to the header and one of them being defined from the header by a second score along a line at right angles to the first score from the inner terminus of the first score to an edge of the tag, a plurality of identical feed finger notches cut through the strip within a band extending longitudinally of the strip, said 40 notches disposed with a notch between adjacent panels in each tag and a notch between each pair of adjacent tags, at least two zones extending longitudinally of the strip across the panels at the respective sides and contiguous with said band in which the material of the strip is continuous, the zone at the header side of the band being closely adjacent said second score whereby upon 50 operation on the strip of a cut-off knife designed to remove all of the strip material within said longitudinal zones successively between tags and between panels, said 55 tags are separated and an elongated slot is provided between panels in each tag, said elongated slot extending from the header transversely of the tag.
